RAKE FOR SHAG RUGS

Mildred Derian, Redondo Beach, Calif., assignor to
J. F. Kerns Industries, South El Monte, Calif.

Filed June 12, 1970, Ser. No. 23,456

Term of patent 14 years

Int. Cl. D4—01

U.S. Cl. D4—3

FIG. 1 is a perspective view of a rake for shag rugs showing my new design;

FIG. 2 is an elevational view thereof;

FIG. 3 is a bottom plan view thereof;

FIG. 4 is a side elevational view thereof; and

FIG. 5 is a view taken in accordance with the section line 5—5 on FIG. 1.

I claim:

The ornamental design for a rake for shag rugs, substantially as shown.
